UNITED STATES PATENT OFFICE.

WILLIAM N. MARSDEN, OF AMSTERDAM, NEW YORK.

GLOVE-TIPPING MACHINE.

No. 828,947.

Specification of Letters Patent.

Patented Aug. 21, 1906.

Application filed November 25, 1905. Serial No. 289,063.

To all whom it may concern:

Be it known that I, WILLIAM N. MARSDEN, a citizen of the United States, residing at Amsterdam, county of Montgomery, and 5 State of New York, have invented certain new and useful Improvements in Glove-Tipping Machines, of which the following is a specification.

The invention relates to such improvements; and it consists of the novel construction and combination of parts hereinafter described and subsequently claimed.

Reference may be had to the accompanying drawings, and the reference characters 15 marked thereon, which form a part of this specification.

Similar characters refer to similar parts in the several figures therein.

Figure 1 is a view in end elevation of a well-known form of glove-sewing machine provided with my novel attachments, the same being drawn on a larger scale than the other figures. Fig. 2 is a front view of the track-plate detached. Fig. 3 is a top plan view of the right-hand end of said track-plate. Fig. 4 is a view in front elevation of the feed-plate removed from the machine. Fig. 5 is a view in rear elevation of the same. Fig. 6 is a top plan view of the machine shown in Fig. 1. Fig. 7 is a view of the finger portion of a glove-blank, showing the reinforce-tips before the same are folded back and stitched to the fingers. Fig. 8 is a similar view after the stitching operation accomplished by the use 35 of my improved attachment. Fig. 9 is a view in front elevation of a broken-away portion of the feed-plate and clamps, showing several finger portions of a glove supported thereupon as the same would appear just after the stitching operation and before the 40 chains of stitching connecting the neighboring fingers have been cut. Fig. 10 is a vertical cross-section of the same, taken on the broken line 10 10 in Fig. 9, showing a finger 45 portion of a glove before the insertion of the stitching.

In the manufacture of certain kinds of gloves it is customary to reinforce the ends of certain of the fingers where most exposed to wear. This is commonly accomplished by making the finger at the point where it is desired to reinforce the same of double thickness of fabric by applying and securing thereto a reinforce piece or tip, which for convenience is made integral with the finger-strip itself and folded back thereupon, the end of

the folded-over tip being stitched to the body of the finger-strip. The operation of thus stitching the reinforce-tips to the body of the finger-strips is accomplished while the glove 60 is yet in the blank form and as a preliminary operation to the formation of the finger-sheaths.

As a desirable mode of procedure to accomplish the stitching of the folded-over finger-tips to the finger-bodies the finger portions of the glove-blank may be folded over the edge of a thin metal plate at about the point where the stitching is to be inserted, with the tips folded back upon the finger-bodies, the edge 70 of the tip being exposed adjacent to the fold-line of the finger-body just above the edge of said plate, in which position the parts are held by spring-clamps while the blank thus mounted upon said plate is fed to a sewing-machine which performs the stitching operation.

My invention relates in certain of its features to sewing-machine attachments for thus supporting and feeding to the machine 80 such glove-blanks and in certain other features to attachments for separating and releasing the glove-blanks at the conclusion of such stitching operation.

The principal object of the invention is to 85 relieve the operator from much of the work attendant upon the preparation of the blanks for their presentation to the sewing mechanism and the subsequent releasing and separating of the blanks.

Other objects of the invention will appear in connection with the following description.

Referring to the drawings, wherein the invention is shown in its preferred form, I have shown my attachment applied to a well-known type of glove-sewing machine wherein the work is adapted to be fed between a pair of disks 1 and 2, the former being rotatively mounted upon the upper end of a movable arm 3 and the latter being fixed upon a 95 spindle 4, rotatively mounted in a bracket 5, fixed upon the body or frame 6 of the machine, which spindle has fixed thereon a ratchet 7, adapted to be given a step-by-step rotative movement by means of the pawl 8, 100 which is operatively connected with the driving mechanism of the machine in the usual manner.

The machine is of the type adapted for overedge stitching, and the needle 9 and 110 looper 10 operate just above the disks 1 and 2 adjacent to their point of contact with each

other in position for the needle to play through the exposed edge of the goods clamped between and fed by the said disks.

The construction of a machine of this type 5 being well understood in the art, further description of the same will be unnecessary.

In carrying out my invention I mount in fixed position by means of screws 11 upon the bed of said machine in a vertical plane 10 extending about midway between the disks 1 and 2 and at right angles to the needle a track-plate 12, having formed thereon by a series of grooved rollers 13 a track or way for the feed-plate 14, the base of which is adapted to 15 freely fit the grooves in said rollers, the feed-plate being adapted to rest upon said rollers in an upright position with its upper edge between the disks 1 and 2.

A step-by-step positive feed movement is 20 imparted to said feed-plate through a gear-rack 15, fixed upon the back thereof, adapted to be engaged by a pinion 16, fixed upon the lower end of the spindle 4, said plate being adapted to be successively fed through, removed from, and returned to the machine.

The feed-plate is adapted to have applied thereto in the manner above referred to the glove-blanks with their finger-bodies folded over the upper edge of the plate and the finger-tips held in proper position upon the folded-over portions of the finger-bodies to accomplish the stitching of the edge of the tip to the finger-body as said plate is fed through the machine.

35 As a means for holding the finger-tips in their proper relation to the folded-over portion of the respective finger-bodies I have shown the feed-plate provided on its front side with a separate spring-clamp 17 for each 40 finger to be tipped, said clamps being attached to said plate at their lower ends by means of screws 18 and being of bowed form with their upper ends adapted to engage and press firmly against the front side of the feed-plate, the 45 folded-over portion of the glove-finger, and its reinforcing-tip, as shown in Fig. 10.

I have shown the feed-plate thus provided with twelve clamps 17, adapting the plate to simultaneously hold all of the parts of a pair 50 of gloves to be thus provided with the reinforcing members.

The little fingers of the gloves are not ordinarily reinforced.

Certain of the clamps are considerably 55 wider than the others, as the clamps 17^a for the index-fingers, which are ordinarily cut of double width, and 17^b, which represents the clamps for the thumbs, cut separately from the other parts of the glove.

60 The clamps 17 are adapted to be all simultaneously opened by means of a shaft or plate 19, eccentrically mounted in bearings upon the front of the feed-plate and adapted to be operated by an offset arm 20. By rocking said shaft or plate 19 by means of the arm 20

the upper ends of the clamps are forced away from the feed-plate to permit the insertion of the goods between the plate and clamps, which insertion is accomplished by hand by the operator.

I have shown each clamp 17 provided with a separate automatically-operated catch for holding the same in open position, the same comprising a lever 21, pivoted upon the clamp at 22, and adapted in one position to pass 70 freely through a slot 23 in the feed-plate.

The lever is so overbalanced at its inner end that it normally assumes a position so depressed as to engage the edge of the feed-plate below the slot 23, in which position it is 75 adapted to hold the clamp open. The lever, however, can be rocked by the hand of the operator to bring it into line with the slot 23 to permit the clamp to be closed by its resilient force. The object of this construction 80 is to enable the operator upon the completion of the stitching operation to simultaneously free the clamped members by means of the cam-plate 19 and at the same time to lock 85 said clamps in open position by means of the automatic action of the levers 21, whereby the clamps are all held open independently of each other when the cam-plate 19 is restored to its normal position. This permits of 90 quick removal of the work from the plate. 95

In applying the work to the plate, however, each finger or thumb portion with its reinforcing-tip must be adjusted separately by the operator, and as soon as adjusted it can be clamped in position by its appropriate 100 clamp, which is rendered effective for this purpose by a rocking movement imparted to the catch 21 by the operator to bring the same into line with its slot 23. When the finger portions have been thus clamped in 105 position, the body portion of the glove is drawn over the edge of the feed-plate into engagement with a row of pins 24 on the back side of said plate, which hold the finger portions of the glove stretched over the edge 110 of the feed-plate, in which position the dependent body portions of the glove are confined between the back side of the feed-plate and a shield 25 mounted thereon, adapted to protect the glove from becoming entangled 115 or soiled by contact with the gears or other feeding mechanism.

As a means for automatically opening all the clamps upon the completion of the stitching operation I have shown mounted upon 120 the track-plate 12 an inclined block 26 in the path of and adapted to engage the offset arm 20 and automatically operate through the same the cam-plate 19 immediately after the last feed-plate-supported member of the 125 work has been stitched, the feed-plate being thus delivered from the machine at the end of its movement therethrough, with the clamps open to permit the immediate removal of the work by the operator.

As the stitching operation is continuous during the passage of the feed-plate through the machine, the neighboring finger portions are upon leaving the needle connected by a 5 chain of stitching C, which bridges the interval between the neighboring finger portions, which chain must be broken or cut subsequently to the stitching operation. The cutting of said chains of stitching may be accomplished by hand or in any known manner. I have shown means whereby the same can be accomplished automatically during the 10 progress of the passage of the feed-plate through the machine. In carrying out this 15 feature of my invention I mount a sharply-pointed knife 27 upon a knife-bar 28, reciprocatory in a slideway 29, pivotally mounted at 30 upon the frame of the machine, through which slideway the knife-bar is adapted to be 20 reciprocated by means of an arm 31, projecting upwardly from a slide-bar 32, reciprocatory in fixed slideways 33 and 34, said slide-bar being adapted to be automatically operated in a direction to accomplish a forward 25 movement of the knife by means of a coil-spring 35, interposed between one of said slideways 34 and a collar 36, fixed upon said slide-bar.

The slide-bar is adapted to be operated in 30 the opposite direction by the engagement of the follower 37, mounted upon its end, with a plate 38 fixed upon the back of the feed-plate, successive cam-like portions of which act upon said slide-bar in opposition to the 35 spring 35.

In addition to the reciprocating motion in a horizontal line thus imparted to the knife an up-and-down reciprocating motion is imparted thereto by oscillating the slideway 29 40 upon the pivot 30, which is accomplished by means of a slide-bar 39, vertically arranged in fixed slideways 40 and 41, having its upper end pivotally connected at 42 with the oscillating end of said knife-slideway 29 and having an arm 43 offset from its lower end and provided with a follower 44, engageable with a cam-like projection on the plate 45, fixed 45 upon the back of the feed-plate and serving at certain times to lift said arm, slide-bar, and knife-slideway 29 against the force of the coil-spring 46, interposed between the slide-way 40 and a collar 47, fixed upon said slide-bar.

The cam-like projections on the two plates 50 38 and 45 form gradually-inclined risers terminating abruptly at their highest points, and they are so arranged and proportioned that as each interval between neighboring fingers on the glove carried by the feed-plate 55 is brought opposite the knife the follower 44 passes off from the tip of one of said projections to the bottom of the next incline or projection, causing a quick descending movement of the knife to its lowermost position, 60 immediately after which the follower 37

passes from the highest point of one of said projections and is forced by the spring 35 to the bottom of the next incline or projection, causing a quick forward movement of the knife, whereby its point is forced beneath the 70 chain of stitching connecting said two fingers. Thereafter as the two followers 44 and 37 ride up the respective inclines on the next succeeding projections the knife is raised so as to sever said chain and is then gradually 75 drawn back in preparation for the next succeeding forward stroke.

By the use of my invention it is necessary for the operator only to apply the goods to the feed-plate and insert the same in the machine. The knife is provided with an overhanging shield 48 for the protection of the operator. By employing a plurality of such feed-plates the operator can be filling one feed-plate with the goods while a previously-filled plate is passing through the machine, so that a material saving in time and labor is 85 accomplished.

In the drawings, 46 represents the finger-bodies, 47 the reinforce-tips, and 48 the stitching connecting the edge of the tip with the finger-body.

What I claim as new, and desire to secure by Letters Patent, is—

1. In a machine of the class described, the 95 combination with the stitch-forming mechanism; of a work-supporting feed-plate; a plurality of work-clamps mounted upon said feed-plate; means for feeding said plate past the stitch-forming mechanism; and a clamp-opening member engageable with all of said clamps simultaneously.

2. In a machine of the class described, the 105 combination with the stitch-forming mechanism; of a work-supporting feed-plate; a plurality of work-clamps mounted upon said feed-plate; means for feeding said plate past the stitch-forming mechanism; a clamp-opening member engageable with all of said clamps simultaneously; and means for automatically operating said clamp-opening member.

3. In a machine of the class described, the 115 combination with the stitch-forming mechanism; of a work-supporting feed-plate; a plurality of work-clamps mounted upon said feed-plate; a separate automatically-operating catch for locking each clamp in open position; and means for simultaneously opening all of said clamps.

4. In a machine of the class described, the 125 combination with the stitch-forming mechanism; of a work-supporting feed-plate; a plurality of work-clamps mounted upon said feed-plate; a separate automatically-operating catch for locking each clamp in open position; and automatically-operated means for opening all of said clamps simultaneously.

5. In a machine of the class described, the 130 combination with a work-supporting feed-

- plate provided with an aperture; of a work-clamp mounted upon said plate; and an automatically-operating catch for locking said plate in open position comprising a lever pivoted upon said clamp and overbalanced to engage said feed-plate at one side of said aperture and movable into line with said aperture which is adapted to receive the same to permit the clamp to be closed.
- 5 6. In a machine of the class described, the combination with the stitch-forming mechanism having a horizontally reciprocating needle; of a work-supporting feed-plate; a track below said needle adapted to support said feed-plate in upright position with its upper edge adjacent to said needle; means for moving said feed-plate past said stitch-forming mechanism; a work-clamp on said feed-plate; and automatically-operated clamp-15 opening mechanism.
- 10 7. In a machine of the class described, the combination with the stitch-forming mechanism; a work-supporting feed-plate; means for moving said feed-plate past the stitch-forming mechanism; and means for clamping the work upon said feed-plate; of a cutter movable across the path of the feed-plate-supported work; and means for automatically operating said cutter at certain times.
- 20 8. In a machine of the class described, the combination with the stitch-forming mechanism; a work-supporting feed-plate; means for moving said feed-plate past the stitch-forming mechanism; and means for clamping the work upon said feed-plate; of a cutter movable across the path of the feed-plate-supported work; and means for automatically operating said cutter at certain times.
- 25 9. In a machine of the class described, the combination with the stitch-forming mechanism; a work-supporting feed-plate; means for moving said feed-plate past the stitch-forming mechanism; and means for clamping the work upon said feed-plate; of a cutter movable across the path of the feed-plate-supported work; and means for automatically operating said cutter at certain times.
- 30 10. In a machine of the class described, the combination with the stitch-forming mechanism; a work-supporting feed-plate; means for moving said feed-plate past the stitch-forming mechanism; and means for clamping the work upon said feed-plate; of a cutter movable across the path of the feed-plate-supported work; and means for automatically operating said cutter at certain times.
- 35 11. In a machine of the class described, the combination with the stitch-forming mechanism; a work-supporting feed-plate; means for moving said feed-plate past the stitch-forming mechanism; and means for clamping the work upon said feed-plate; of a cutter movable across the path of the feed-plate-supported work; and means for automatically operating said cutter at certain times.
- 40 12. In a machine of the class described, the combination with the stitch-forming mechanism; a work-supporting feed-plate; means for moving said feed-plate past the stitch-forming mechanism; and a plurality of clamps for holding separate portions of the work upon said plate; of a cutter movable across the path of the feed-plate-supported work; and means for automatically imparting to said cutter a cutting movement at certain times when intervals between said clamps are presented opposite said cutter.
- 45 13. In a machine of the class described, the combination with the stitch-forming mechanism; a work-supporting feed-plate; means for moving said feed-plate past the stitch-forming mechanism; and means for clamping the work upon said feed-plate; of a cutter movable across the path of the feed-plate-supported work; a cutter-supporting bar; a vertically-movable slideway for the cutter-bar; feed-plate-actuated mechanism for reciprocating said cutter-bar in said slideway; and feed-plate-actuated mechanism for imparting to said slideway a vertical movement at certain times.
- 50 14. In a machine of the class described, the combination with the stitch-forming mechanism; a work-supporting feed-plate; means for moving said feed-plate past the stitch-forming mechanism; and means for clamping the work upon said feed-plate; of a cutter movable across the path of the feed-plate-supported work; a cutter-supporting bar; a vertically-movable slideway for the cutter-bar; feed-plate-actuated mechanism for reciprocating said cutter-bar in said slideway; and feed-plate-actuated mechanism for imparting to said slideway a vertical movement at certain times.
- 55 15. In a machine of the class described, the combination with the stitch-forming mechanism; a work-supporting feed-plate; means for moving said feed-plate past the stitch-forming mechanism; and means for clamping the work upon said feed-plate; of a cutter movable across the path of the feed-plate-supported work; a cutter-supporting bar; a vertically-movable slideway for the cutter-bar; feed-plate-actuated mechanism for reciprocating said cutter-bar in said slideway; and feed-plate-actuated mechanism for imparting to said slideway a vertical movement at certain times.
- 60 16. In a machine of the class described, the combination with the stitch-forming mechanism; a work-supporting feed-plate; means for moving said feed-plate past the stitch-forming mechanism; and means for clamping the work upon said feed-plate; of a cutter movable across the path of the feed-plate-supported work; a cutter-supporting bar; a vertically-movable slideway for the cutter-bar; feed-plate-actuated mechanism for reciprocating said cutter-bar in said slideway; and feed-plate-actuated mechanism for imparting to said slideway a vertical movement at certain times.
- 65 17. In a machine of the class described, the combination with the stitch-forming mechanism; a work-supporting feed-plate; means for moving said feed-plate past the stitch-forming mechanism; and means for clamping the work upon said feed-plate; of a cutter movable across the path of the feed-plate-supported work; a cutter-supporting bar; a vertically-movable slideway for the cutter-bar; feed-plate-actuated mechanism for reciprocating said cutter-bar in said slideway; and feed-plate-actuated mechanism for imparting to said slideway a vertical movement at certain times.

In testimony whereof I have hereunto set my hand this 20th day of November, 1905.

WILLIAM N. MARSDEN.
